(57) **CLAIM**

The ornamental design for a light bulb installation device, as shown and described.

DESCRIPTION

FIG. 1 is a front perspective view of a light bulb installation device according to the present invention.

FIG. 2 is a side elevation view of the light bulb installation device illustrated in FIG. 1.

FIG. 3 is another side elevation view of the light bulb installation device illustrated in FIG. 1.

FIG. 4 is a rear elevation view of the light bulb installation device illustrated in FIG. 1.

FIG. 5 is a front elevation view of the light bulb installation device illustrated in FIG. 1.

FIG. 6 is a top plan view of the light bulb installation device illustrated in FIG. 1; and,

FIG. 7 is a bottom plan view of the light bulb installation device illustrated in FIG. 1.

The broken lines depict a connector to be used in connection with the light bulb installation system and does not form a claimed feature of the present invention.
